UNITED STATES PATENT OFFICE.

FRED ASHWORTH, OF BEVELEY, MASSACHUSETTS, ASSIGNOR TO UNITED SHOE MACHINERY COMPANY, OF PATERSON, NEW JERSEY, A CORPORATION OF NEW JERSEY.

SEWING-MACHINE.

1,233,539.

Specification of Letters Patent. Patented July 17, 1917.

Application filed May 24, 1913. Serial No. 769,566.

To all whom it may concern:

Be it known that I, FRED ASHWORTH, a citizen of the United States, residing at Bevelry, in the county of Essex and State of Massachusetts, have invented certain new and useful Improvements in Sewing-Machines; and I do hereby declare the following to be a full, clear, and exact description of the invention, such as will enable others skilled in the art to which it appertains to make and use the same:

This invention relates to wax thread sewing machines, and more particularly to outsole shoe sewing machines of the class employed in sewing the outsole to the welt of a welted shoe.

One object of the present invention is to provide shoe sewing machines of this class with an improved presser foot mechanism by which with the parts of the machine in the position which they assume at a point in a cycle of operations when the presser foot is normally locked in work engaging position the presser foot may be unlocked and lifted to allow the finished work to be removed or the work which is being operated on to be adjusted, and which will maintain the presser-foot in an unlocked condition until it has been lowered into engagement with the work.

Another object of the invention is to provide shoe sewing machines with improved mechanism for lifting the presser-foot upon stopping the machine for holding the presser foot in raised position while the machine is at rest and for releasing the presser foot to allow it to descend upon the work upon starting the machine.

A still further object of the invention is to provide shoe sewing machines with improved mechanism for bringing the machine to rest at a predetermined point in a cycle of operations without undue shock or jar, and for raising the presser-foot from the work as the machine comes to rest.

With these and other objects in view, the invention contemplates the provision of various novel and improved features clearly set forth in the following description, and particularly pointed out in the claims, the advantages of which will be obvious to those skilled in the art.

In the accompanying drawings illustrating a machine embodying the several fea-

tures of the invention in their preferred forms;

Figure 1 is a detailed view in side elevation illustrating particularly the presser-foot mechanism;

Fig. 2 is a plan view, partly in section, illustrating particularly the slow speed driving mechanism and the mechanism for raising the presser-foot upon stopping the machine;

Fig. 3 is a sectional view taken substantially on the line 3—3 of Fig. 2, showing the mechanism shown in Fig. 2, and in addition the presser-foot lever and certain parts associated therewith;

Fig. 4 is a sectional view taken substantially on the line 4—4 of Fig. 2, showing the mechanism illustrated in Fig. 2, and also the tension device and the connecting mechanism through which the tension device is actuated to release the tension as the machine is brought to rest;

Fig. 5 is a sectional view taken substantially on the line 5—5 of Fig. 2.

Fig. 6 is a view in side elevation of the complete machine.

The sewing machine illustrated in the drawing is an outsole lockstitch curved hook needle machine substantially the same in general construction, arrangement and mode of operation, as the machine illustrated and described in applicant's Patent No. 1,139,909, Feb. 1, 1916. In this application only so much of the machine has been illustrated as has been considered necessary to give a clear understanding of the invention. The work-support of the machine is indicated at 1, the presser-foot at 2, the curved hook needle at 3, and the awl at 4. The presser foot is actuated in substantially the same manner during the sewing operation as in the machine illustrated and described in the above patent. The presser-foot is mounted upon the upper arm of the presser-foot lever 5, which is pivoted upon the stud 6, and the presser-foot is actuated during the sewing operation of the machine by mechanism connected by a link 7 with the lower arm of the presser-foot lever. During each cycle of operations, starting immediately after the work has been fed, the presser-foot is moved into engagement with the work, is held with a light spring pressure against the work, is depressed positively a prede-

terminated distance, is locked in depressed position, and is then unlocked and raised from the work. The mechanism for actuating the presser-foot in this manner comprises a pivoted lever supported upon a movable fulcrum 9 and connected by the link 7 with the lower arm of the presser-foot lever. The presser-foot is moved into engagement with the work and is pressed 5 lightly against the work by means of a tension spring 10 attached at one end to a pin 11 projecting from an angularly adjustable rod 12 and having its other end connected by a link 13 with the lower end of the lever 8. The presser-foot is pressed down positively against the work a predetermined distance and is lifted from the work by the action of a lever 14 pivoted on a stud 15, the lower end of which is connected by a 10 link 16 with the upper end of the lever 8. The fulcrum 9 for the lever 8 is carried at the forward end of a longitudinally movable fulcrum bar 17, which moves in guides in the arms of a yoke 18. The fulcrum bar 17 is unlocked so that it can move longitudinally when the presser-foot is moved into engagement with the work and while it is pressed lightly upon the work by the spring 10 and is locked during the action of the 15 lever 14 to depress the presser-foot positively against the work and to lift it from the work. The fulcrum bar is provided with a series of screw threads 19 of steep pitch, and a nut 20 is threaded on the fulcrum bar 17 and arranged between the arms of the yoke 18. When the nut 20 is free to rotate on the fulcrum bar, the fulcrum bar is free to move longitudinally through the yoke. The fulcrum bar is locked against longitudinal 20 movement by locking the nut against rotation on the bar. The nut is locked against rotation to lock the fulcrum bar during each cycle of operation, by means of a lever 21, pivoted at 22 on the yoke and carrying a 25 roll 23 for engagement with the periphery of the nut. The roll 23 is mounted on the lever 21 between the nut and the axis of the lever at a point such that the distance between the axis of the lever and the nut-en- 30 gaging face of the roll is slightly greater than the distance between the axis of the lever and the nut. When the lever 21 is swung toward the rear of the machine, the roll 23 will wedge against the periphery of the nut 35 and thereby securely hold the nut from rotation. The upper end of the lever 21 is connected by a link 24 with the arm 25 of a lever 25-26 pivoted on a shaft 27. A rod 28 is pivotally connected with the end of the 40 arm 26 and is arranged to move through a guide in a block 29 on the frame. The lever 25-26 is turned about the shaft 27 in a direction to swing the lever 21 to the rear, and lock the nut on the fulcrum bar by the 45 action of a coiled spring 30 surrounding 45 rod 28 and interposed between the block 29 and a collar on the rod so that it acts to lift the rod and the arm 26 and swing the arm 25 and the lever 21 toward the rear of the machine. The lever 25-26 is turned in the opposite direction to swing the lever 21 forwardly and unlock the nut 20 so that the fulcrum bar may move freely through the guides in the yoke 18 by the actuation of a lever 31 pivoted on the shaft 27 which carries an abutment screw 32 arranged to engage the upper face of the arm 26 of the lever 25-26. When the lever 31 is swung downwardly about the shaft 27, it will swing the lever 25-26 in a direction opposed to the action of the spring 30. The lever 31 is actuated to unlock the nut on the fulcrum bar during each cycle of stitch forming operations by a cam lever 33 also pivoted on the shaft 27 and provided with a cam roll 34 acted on by a cam carried by the cam shaft of the machine. The hub of the lever 33 is provided with a shoulder 35 which, when the lever 33 is swung to the right (Fig. 1) engages a shoulder 36 on the hub 30 of the lever 31, thereby swinging the lever 31 downwardly about the shaft 27. 50 To enable the presser-foot to be unlocked and lifted after the machine has been stopped or upon stopping the machine at 95 a point in a cycle of operations when it is normally locked firmly in work-engaging position, a lever 37 is pivoted upon the stud which supports the presser-foot lever and is provided with a roll 38, mounted upon the 100 end of its lower arm, which is arranged to engage behind the lower arm of the presser-foot lever 5 when the upper arm of the lever 37 is swung rearwardly. The upper arm of the lever 37 is connected by a link 38a 105 with the upper arm 39 of a lever 39-40 fixed upon a stud 41 mounted to turn in bearings on the frame. The end of the arm 40 is formed with a cam face 42 which is arranged to engage a roll 43 carried by the 110 lever 31. The connection between the lever 31 and the lever 33 permits the lever 31 to be swung downwardly about the shaft 27 independently of the lever 33. The forward portion of the cam face 42 is sharply inclined to the path of the end of the arm 40 while the rear portion of said face is substantially concentric with the path of the end of the arm so that as the arm 40 swings forwardly the roll will be depressed and the 115 lever 31 swung downwardly to unlock the nut on the fulcrum bar by the engagement of the inclined portion of the cam face 42 with the roll 43 and when the roll reaches the portion of said face which is concentric with the path of the end of the arm 40 the further movement of the arm will not affect the lever 31. The parts are so constructed and arranged that as the upper arm of the 120 lever 37 and the arm 39 of the lever 39-40 125 130

are swung rearwardly the lever 31 is first actuated to unlock the nut on the fulcrum bar by the engagement of the forward inclined portion of the cam face 42 with the roll 43 and after the portion of said face which is concentric with the path of movement of the end of the arm 40 reaches the roll 43 the roll 38 engages the rear side of the lever arm of the presser foot lever and 10 the presser-foot is then lifted by the continued movement of the lever 37. The presser-foot may be unlocked and lifted by the operator by a manual manipulation of the lever 37 which serves as a hand lever or 15 the parts may be automatically actuated to unlock and lift the presser-foot as herein-after described. When the parts are released, the presser-foot is brought down upon the work by the action of the spring 20 10 and the levers 37 and 39-40 are returned to their normal positions by the coiled spring 44. When the presser-foot is descending the roll 43 does not leave the portion of the cam face 42 which is substantially concentric with the path of movement of the end of the arm 40 until the presser-foot is 25 engaged with the work. It is, therefore, impossible for the spring 30 to act to lock the presser-foot until the presser-foot has 30 moved into work-engaging position.

The machine is driven during the sewing operation from a main driving shaft 45 journaled in bearings in the base of the machine by means of a belt 46 passing about a pulley 47 which is arranged to be driven through driving connections from the main driving shaft and about a pulley 48 secured to the end of the main shaft 49 of the machine. The pulley 47 is connected through 40 intermeshing beveled gears 50 with a sleeve 51 mounted on the main driving shaft 45, to which sleeve is secured one member 52 of the main driving clutch. The other member 53 of the main driving clutch is mounted to 45 rotate with the main driving shaft, and is movable longitudinally of said shaft into and out of engagement with the clutch member 52. The engagement of the clutch member 53 with the coöperating clutch member 52 is controlled by a clutch operating wedge 54 which is connected with and actuated from the treadle 55. When the treadle is depressed the clutch members are 50 engaged and the machine is driven at a speed depending upon the pressure applied to the treadle by the operator. When the treadle is released the clutch members are disengaged and the main shaft 49 of the machine is thereby disconnected from the 55 driving shaft 45. The shaft 45 is driven from the power shaft by means of a belt passing about a pulley 56 fixed upon the shaft 45. 57 indicates a loose pulley mounted upon the shaft 45.

60 The upward movement of the treadle when

it is released not only disconnects the main shaft of the machine from the main driving shaft located in the base thereof, but also throws into operation mechanism by which the main shaft is slowed down to a predetermined slow speed then driven at slow speed in a forward direction and finally stopped at a predetermined point in a cycle of operations. The mechanism for slowing down the shaft and for driving it at slow speed comprises a friction clutch consisting of a driving friction clutch member 58 loosely mounted on the main shaft 49, which is constantly driven at a predetermined slow speed in a forward direction and a coöperating driven friction clutch member 59 mounted on the shaft 49 to rotate with the shaft. A spiral gear 60 is formed integral with the clutch member 58 and said clutch member is driven by means of a spiral pinion 61 meshing with said gear. The spiral pinion 61 is mounted upon a shaft 62 which carries a pulley 63 and the shaft 62 is constantly driven from the pulley 56 by means of a belt 64 passing about a pulley 65 formed on the hub of the pulley 56 and about the pulley 63. The clutch member 59 is secured to a sleeve 66 which is free to slide longitudinally of the shaft 49 but is connected to rotate with the shaft by means of a block 67 secured in the pulley 48, the inner end of which is engaged between lugs 68 projecting outwardly from the sleeve 66. The sleeve 66 is normally maintained in a position such that the clutch member 59 is disengaged from the clutch member 58 by means of a coiled spring 69 seated in a recess in the block 67 acting against the head of a pin or bolt 70 slidably mounted in the block 67 and having a plate 71 secured to its inner end which engages the inner faces of the lugs 68.

When the members of the slow speed friction clutch are engaged they first act as a friction brake to slow down the speed of the main shaft of the machine until it is rotating at the speed of the slow speed driving clutch member, after which the main shaft is driven at slow speed in a forward direction by the slow speed driving clutch member until the machine is brought to stopping position when the members of the slow speed clutch are disengaged and the rotation of the main shaft is stopped. The clutch members 58 and 59 are engaged at a predetermined point in the rotation of the main shaft of the machine and the said clutch members are disengaged and the rotation of the shaft arrested at the end of a predetermined interval after the engagement of the clutch members, so that the shaft is always slowed down and its rotation finally arrested in a uniform manner. The mechanism for engaging and disengaging the clutch members 58 and 59 at predetermined points in the rotation of the shaft com-

prises a timing cam consisting of a cam groove 72 formed in the sleeve 66 in which engages a cam roll 73 carried by one arm of the bell crank lever 74 pivoted in a stud 75, the other arm of which is provided with a recess 76 arranged to receive the head of a locking pin 77. The locking pin 77 is mounted to slide vertically in the rear end of a slide 78, and is moved upwardly in said 10 slide into engagement with the recess 76 in the arm of the bell crank lever by a coiled spring 79. The slide 78 is provided with a reduced extension 80 arranged to slide through an adjustable sleeve 81 threaded 15 into the frame. The rearward movement of the slide 78 is limited by a stop nut 82 which engages the end of the sleeve 81 and the slide is held in normal position in the frame by means of a coiled spring 83 surrounding 20 the reduced portion of the slide and interposed between a shoulder on the slide and the inner end of the sleeve 81. By adjusting the sleeve 81 the slide 78 may be adjusted so as to bring the locking pin into 25 position to register with the recess 76 in the arm of the bell crank lever at the proper time in a cycle of operations and by adjusting the nut 82 the tension of the spring 83 may be varied.

30 The locking pin is controlled from the treadle so that when the treadle is depressed and the main driving clutch in the base of the machine is engaged to drive the machine, the locking pin is held down out of engagement with the recess 76 and the bell crank lever 74 is then oscillated idly by the cam 72. When the treadle is released and rises to disconnect the main shaft of the machine from the main driving shaft, the locking 40 pin is engaged with the recess 76 and the bell crank lever is thereby locked to the slide 78. When the bell crank lever 74 and the slide 78 are thus locked together the cam 72 acting upon the roll 73 will force the 45 sleeve 66 longitudinally of the shaft 49 in the direction to bring the clutch member 59 into engagement with the driving clutch member 58. The force with which the slow speed clutch members are engaged will depend 50 upon the tension of the spring 83 and this may be adjusted so that the shaft will be slowed down to the speed of the slow speed driving clutch member and will be driven by said member in a forward direction before the slow speed clutch members are disengaged and the rotation of the main shaft is arrested. The timing cam 72 and the mechanism coöperating therewith act to bring the clutch members 58 and 59 into engagement at a definite point in the rotation 60 of the shaft. When the shaft has been slowed down to the slow speed of the slow speed driving clutch member and while it is driven at slow speed by said member the 65 continued rotation of the cam 72 will cause

the disengagement of the clutch members at the end of a definite interval after they were engaged.

The mechanism for controlling the engagement of the locking pin with the recess 76 in the arm of the bell crank lever comprises a link 84 pivotally connected with a block secured to the lower end of the locking pin and connecting said pin with the arm 85 of a three-armed lever 86 pivoted upon a 75 stud 87. This lever is provided with a second arm 88 upon the end of which is mounted a roll 89. The locking pin is held down out of engagement with the recess 76 in the arm of the bell crank lever, while the treadle 80 is depressed and the main driving clutch in the base of the machine is engaged by the engagement with the roll 89 of a curved face 90 formed upon the outer end of an arm 91 pivoted on a stud 92 and connected 85 with the forward end of the treadle by means of a rod 93. The curved face 90 is formed substantially concentric with the path of movement of the outer end of the arm 91 so that the movements of the treadle 90 in producing variations in the speed of the machine will not affect the position of the locking pin. When the treadle is released and rises, the arm 91 is swung upwardly to disengage the outer end thereof from the roll 89 and the locking pin is then forced upwardly in the slide 78 by the spring 79 into engagement with the under side of the arm of the bell crank lever and when the recess 76 registers with the head of the pin, 100 the pin snaps upward into the recess. Fig. 4 shows clearly the position of the parts when the treadle is released and the machine is at rest. When the treadle is depressed, to start the machine, the outer end 105 of the arm 91 engages the roll 89 and swings the three-armed lever 86 to disengage the locking pin from the recess in the arm of the bell crank lever. The parts are constructed and arranged so that the locking 110 pin is disengaged from the recess 76 before the main driving clutch is engaged, and the continued downward movement of the treadle to engage the main driving clutch brings the curved face at the outer end of 115 the arm 91 into engagement with the roll 89.

To enable the main shaft to be rotated manually whenever it is desirable, the outer end of the arm 91 is formed with a locking recess 94 to receive the roll 89 and lock the 120 arm from upward movement at a time when the locking pin is disengaged from the recess in the arm of the bell crank lever and when the members of the main driving clutch are disengaged.

The mechanism for lifting the presser foot upon stopping the machine comprises a lever 95 mounted upon a rocking sleeve 96 carried upon a stud 97 arranged substantially parallel with the main shaft 49 of the 130

machine so that the lever 95 is arranged to swing upon an axis substantially parallel with the axis of said shaft. A cam 98 is mounted on the main shaft 49 of the machine to engage the outer end of the lever 95 and swing said lever and the sleeve 96 on which it is carried to the left, Fig. 4, about the stud 97. The sleeve 96 carries an arm 99 which is connected by a link 100 with the arm 101 of a lever 102 pivoted upon a stud 103. The pin or bolt 104 which connects the link 100 with the arm 101 is provided with an extension on its head to engage a stop screw 105 mounted on an arm 106 fixed to the shaft 41. When the lever 95 is actuated by the engagement of the cam 98 therewith, the arm 106 and shaft 41 will be actuated to swing the lever 39—40 in a direction to unlock and lift the presser-foot.

The lever 95 is actuated by the cam 98 as the shaft is executing its final forward movement just before it is brought to rest. While the treadle is depressed to maintain the main shaft of the machine in driving connection with the main driving shaft in the base of the machine, the lever 95 is held out of the path of the cam and removed into the path of the cam as the treadle is released and rises to throw into action the mechanism for slowing down the shaft and driving it forward at slow speed to stopping position. To enable the lever 95 to be moved into and out of the path of the cam said lever is pivotally connected with the sleeve 96 by pivot pins 107 secured in arms on the lever 95 and arranged at right angles to the axis of the sleeve, the inner ends of which engage in cylindrical sockets in the sleeve 96. The lever 95 is provided with a laterally extending arm 108, the end of which projects forwardly at an angle to the main portion thereof across the end of the stud 97 and carries an abutment screw 109 arranged substantially in line with the axis of the stud. The lever 95 is maintained out of the path of the cam 98 when the machine is running normally by the engagement of an arm 110 of the three-armed lever 86 with the end of the screw 109. When the treadle is depressed the three-armed lever 86 is actuated by the engagement of the arm 91 with the roll 89 to lift the arm 110 and swing the lever 95 about the pivot pins 107 so as to place the end of the lever at one side of the path of the cam 98, and the lever 95 is held in this position while the roll 89 is engaged with the curved face of the outer end of the arm 91. When the treadle is released and rises to release the arm 91 from the roll 89 and the locking pin rises under the influence of the spring 79, the arm 110 of the three-armed lever is depressed and the lever 95 is swung into the path of the cam 98 by a spring 111 connected at one end

with the arm 108 of the lever. The arm 99 is provided with a shoulder 112 which engages the rear side of the lever 95, thereby taking the strain from the pivot pins 107 when the lever 95 is actuated by the cam 98. 70

The movement of the shaft is finally arrested by the engagement of a projection or lug 113, carried by the main shaft 49, with the end of the arm 95. This projection is arranged in the plane of rotation of the cam 98 so that the movement of the lever 95 to carry it into and out of the path of the cam will also carry it into and out of the path of the lug. The cam 98 and lug 113 act in co-operation with the lever 95 as a friction 80 brake and a positive stop to slow down and stop the main shaft of the machine in a predetermined position.

To further check the rotation of the shaft before the lug 113 engages the end of the lever 95, the lever 102 is provided with a second arm 114 which carries an abutment screw 115 for engagement with the arm 116 of a bell crank lever pivoted on the stud 75. The other arm 117 of this bell crank carries 90 a brake shoe 118 arranged to engage the inner face of the pulley 48. When the lever 95 is actuated by the cam to swing the arm 101 of the lever 102 to the rear, the abutment screw at the end of the arm 114 engages the arm 116 of the bell crank 116—117 and the bell crank is actuated to engage the brake shoe 118 with the pulley 48.

In order that there may be very little resistance to the lateral swinging movement of the lever 95 to carry said lever out of the path of cam 98 and lug 113 when the treadle is depressed so that the machine may be started with a comparatively light pressure on the treadle, a gap or recess 119 is formed 100 between the cam 98 and the lug 113 so that the cam is disengaged from the lever before the lever is engaged by the lug. When the lever 95 has been actuated by the cam to lift the presser-foot the parts of the presser-foot mechanism are held in position so that the end of the lever 95 does not drop into the recess 119 by a latch 120 fixed upon a fulcrum stud 121 and having a catch projection 122 which engages in front of an extension 115 of the head on the pivot pin 104. A horizontal arm 123 is fixed to the stud 121 and the latch is moved forward to engage the projection 122 in front of the extension on the head of the pin 104 by the action of the force 120 of gravity on said arm. When the lever 95 is swung about the pivot pins 107 to locate the end of the lever out of the path of the cam 98 and lug 113, the latch is disengaged from the extension on the head of the pin 104 125 to allow the presser-foot to descend upon the work by the engagement of the upper face of a laterally extending lug 125 on the arm 108 of the lever 95 with an abutment screw 126 mounted in the offset end of the arm 123. 130

The driving and stopping mechanism described above is made the subject matter of a divisional application Serial No. 133,161, filed November 24, 1916.

5 The tension devices of the machine illustrated are substantially the same as in the machine disclosed in applicant's patent hereinbefore referred to, and comprise intermeshing gear wheels over and between which 10 the thread passes. The tension is applied by a spring 127 acting on a bell crank lever 128 and the tension is released by actuating said lever in opposition to the action of the spring, all as illustrated and described 15 in the Ashworth patent. In the machine illustrated the tension is released as the presser-foot is lifted upon stopping the machine and is restored when the presser descends upon the work as the machine is 20 started. The horizontal arm 129 of the lever 102 is connected by means of a cord 130 with the bell crank 128. The cord 130 passes through a flexible sheath 131, the ends of which are attached to the frame of the 25 machine. When the arm 101 of the lever 102 is moved to the rear to lift the presser-foot the lever 128 is actuated to release the tension. When the arm 101 of the lever 102 is released and swings forward to allow the 30 presser-foot to descend on the work the lever 128 is released and the tension is restored by the spring 127.

Having explained the nature and object of the invention, and specifically described 35 a machine embodying the same in its preferred form, what is claimed is:

1. A shoe sewing machine, having, in combination, stitch forming devices, a work support, a presser-foot, mechanism for actuating the presser-foot, comprising a pivoted lever, a movable fulcrum for the lever, a 40 spring for locking, and means for unlocking, the fulcrum during each cycle of operations, and means for unlocking the fulcrum and lifting the presser-foot when the presser-foot is normally locked in work-engaging position to allow the work to be removed or adjusted, having provision for preventing the locking spring from acting until the 45 presser-foot has descended on the work after being lifted.

2. A shoe sewing machine, having, in combination, stitch forming devices, a work support, a presser-foot, mechanism for actuating the presser-foot comprising a pivoted lever, a movable fulcrum for the lever, means 55 for locking and unlocking the fulcrum during each cycle of operations, and means for unlocking the fulcrum and lifting the

60 presser-foot when the presser-foot is normally locked in work-engaging position to allow the work to be removed or adjusted having provision for rendering the locking means inactive until the presser-foot has 65 descended on the work after being lifted.

3. A shoe sewing machine, having, in combination, stitch forming devices, a work support, a presser-foot, means for locking and unlocking the presser-foot during each cycle of operations, and means for unlocking and 70 lifting the presser-foot when it is normally locked in work-engaging position to allow the work to be removed or adjusted, comprising a roll carried by a part of the locking mechanism, and a pivoted lever having 75 a cam face arranged to engage said roll and move the same in a radial direction relatively to the lever to actuate the locking mechanism to unlock the presser-foot.

4. A shoe sewing machine, having, in combination, stitch forming devices, a work support, a presser-foot, mechanism for actuating the presser-foot comprising a pivoted lever, a movable fulcrum for the lever, means for locking and unlocking the fulcrum during 80 each cycle of operations, and means for unlocking and lifting the presser-foot when the presser-foot is normally locked in work-engaging position to allow the work to be removed or adjusted, comprising a roll carried by the locking mechanism, and a pivoted lever having a cam face to engage the roll and actuate the locking mechanism to 85 unlock the presser-foot.

5. A shoe sewing machine, having, in combination, stitch forming devices, a work support, a presser-foot, mechanism for actuating the presser-foot during each cycle of operations comprising a pivoted lever, a movable fulcrum for the lever, means for locking and unlocking the fulcrum during 90 each cycle of operations comprising a locking member, a member for actuating the locking member to unlock the fulcrum mechanism connecting the locking member with 95 the actuating member, and means for unlocking and lifting the presser-foot when it is normally locked in work-engaging position to allow the work to be removed or adjusted comprising a third member arranged 100 to actuate the locking member through said connecting mechanism.

6. A shoe sewing machine, having, in combination, stitch forming devices, a work support, a presser-foot, a spring for locking the 115 presser-foot and means for unlocking it during each cycle of operations, and means for unlocking and lifting the presser-foot when it is normally locked in work-engaging position to allow the work to be removed or 120 adjusted, having provision to prevent the locking spring from acting until the presser-foot has descended on the work after being lifted.

7. A shoe sewing machine, having, in combination, stitch forming devices, a work support, a presser-foot, a spring for locking the 125 presser-foot and means for unlocking it during each cycle of operations, and means for unlocking and lifting the presser-foot 130

- when it is normally locked in work-engaging position to allow the work to be removed or adjusted, constructed and arranged to prevent the locking spring from acting until the presser-foot has descended on the work after being lifted and comprising a roll carried by the locking mechanism, and a pivoted lever having a cam face to engage said roll and actuate the locking mechanism to unlock the presser-foot.
8. A shoe sewing machine, having, in combination, stitch forming devices, a work support, a presser-foot, mechanism for locking and unlocking the presser-foot during each cycle of operations, comprising a pivoted lever, a movable fulcrum therefor, a movable fulcrum bar, a locking nut threaded on the bar, means for restraining the nut from movement endwise with the bar, a locking lever for the nut having a contact piece for engagement with the nut arranged so that its nut-engaging face is slightly farther from the axis of the lever than the distance between the axis of the lever and the nut, and means for actuating the lever to wedge the contact piece against the nut and lock the nut on the fulcrum bar.
9. A shoe sewing machine, having, in combination, stitch-forming devices, a work support, a presser-foot, means for locking and unlocking the presser-foot during each cycle of operations, comprising a pivoted lever, a movable fulcrum therefor, a movable fulcrum bar, a nut threaded on the bar, means for restraining the nut from movement endwise with the bar, and wedge-acting means for locking the nut from rotation on the bar to lock the presser-foot.
10. A shoe sewing machine, having, in combination, stitch-forming devices, a presser-foot, a main shaft, driving mechanism therefor, a cam driven by the shaft, connections between the cam and the presser-foot for lifting the presser-foot from the cam comprising a member normally out of operative relation with the cam and movable transversely of the plane of movement of the cam into operative relation therewith, means under the control of the operator for disconnecting the driving mechanism from the shaft and moving said member into operative relation with the cam so as to cause the presser-foot to be raised by the operation of the cam as the main shaft is stopped, means for holding said member out of contact with the cam after the presser foot has been raised, and means for moving said member out of the path of the cam upon starting the machine.
11. A shoe sewing machine, having, in combination, stitch-forming devices, a presser-foot, a main shaft, driving mechanism therefor, a cam driven by the shaft, means for raising the presser-foot from the cam upon stopping the rotation of the main shaft,

comprising a member normally out of operative relation with the cam and movable transversely of the plane of movement of the cam into the path of the cam, means under the control of the operator for disconnecting the driving mechanism and moving said member into operative relation with the cam to raise the presser-foot from the cam, means for holding the presser-foot in the position to which it is raised by the cam, mechanism for stopping the driving shaft after the cam has moved out of engagement with said member, and means for moving said member out of the path of the cam upon starting the machine.

12. A shoe sewing machine, having, in combination, stitch-forming devices, a presser-foot, a main shaft, driving mechanism therefor, a tension device, mechanism for lifting the presser-foot and actuating the tension device to release the tension as the main shaft is stopped, comprising a cam driven by the shaft, a member arranged to be actuated by the cam, movable transversely of the plane of movement of the cam into and out of the path of the cam and normally held out of operative relation with the cam during the sewing operation, connecting mechanism between said member and presser-foot and between said member and the tension device, means under control of the operator for disconnecting the driving mechanism and moving said member into the path of the cam to cause the cam to lift the presser-foot and release the tension as the driving shaft is stopped, means for holding the presser-foot lifted and the tension released after the cam has moved out of engagement with said member, and means for moving said member out of the path of the cam and tripping said holding means to allow the presser-foot to descend on the work and the tension to be restored upon starting the machine.

13. A shoe sewing machine, having, in combination, stitch-forming devices, a presser-foot, a tension device, a main shaft, driving mechanism therefor, means for stopping the rotation of the shaft at a predetermined point and for lifting the presser-foot and releasing the tension as the shaft is stopped, comprising a cam and a stop carried by the shaft, a member arranged to be actuated by the cam to lift the presser-foot to release the tension and to be engaged by the stop to stop the rotation of the shaft mounted for movement transversely of the plane of rotation of the cam and stop into and out of the paths thereof, and normally held out of operative position with relation thereto, means under control of the operator for disconnecting the driving mechanism and moving said member into the paths of the cam and stop, a latch for holding the presser-foot lifted and the tension released after the cam

has moved out of engagement with said member, and means for moving said member out of the paths of the cam and stop and for tripping the latch to allow the presser-foot 5 to descend upon the work and the tension to be restored upon starting the machine.

14. A shoe sewing machine, having, in combination, stitch-forming devices, a presser-foot, a main shaft, high speed driving mechanism for the shaft, a treadle for controlling the connection of the shaft with the high speed driving mechanism, a slow speed clutch comprising a driving clutch member and a driven clutch member connected to rotate with the shaft, a cam carried by one of the clutch members, a clutch operating lever actuated by the cam, a locking pin for rendering the clutch operating lever active to bring the clutch members into engagement when the shaft is disconnected from the high speed driving mechanism, means for controlling the engagement of the locking pin with the clutch operating lever comprising a second lever, a connection between the second lever and the locking pin, a roll carried by the second lever, a pivoted arm for engagement with the roll to actuate the second lever having a curved face for contact with the roll to hold the locking pin out of engagement with the clutch operating lever, a connection between said arm and the treadle for actuating the arm from the treadle, and presser-foot lifting mechanism controlled from the locking pin and acting automatically to lift the presser-foot as the main shaft is brought to rest.

15. A shoe sewing machine, having, in combination, stitch-forming devices, a presser-foot, a main shaft, positive stopping devices for arresting the rotation of the shaft at a predetermined point in its rotary movement, means for checking the rotation of the shaft before it is finally arrested by said devices, comprising coöoperating friction brake members, means for lifting the presser-foot as the rotation of the shaft is arrested, and common means for actuating the presser-foot lifting mechanism to lift the presser-

foot and for operating the brake mechanism 50 to bring the brake members into engagement.

16. A shoe sewing machine, having, in combination, stitch-forming devices, a presser-foot, a main shaft, driving mechanism therefor, a cam driven by the shaft, connections between the cam and the presser-foot for lifting the presser foot from the cam, comprising a member normally out of operative relation with the cam and movable transversely of the plane of movement of the cam into operative relation with the cam to lift the presser-foot by the operation of the cam as the main shaft is stopped, a latch for holding the presser-foot in lifted position 65 after the cam has moved out of engagement with said member, and means for disengaging the latch to allow the presser-foot to descend upon the work and to move said member out of the path of the cam upon 70 starting the machine.

17. A shoe sewing machine, having, in combination, stitch-forming devices, a presser-foot, a main shaft, driving mechanism therefor, a cam driven by the shaft, connections 75 between the cam and the presser-foot for lifting the presser-foot from the cam comprising a member normally out of operative relation with the cam, and movable transversely of the plane of movement of the cam into operative relation therewith, means under the control of the operator for disconnecting the driving mechanism from the shaft, and moving said member into operative relation with the cam to raise the 80 presser-foot by the operation of the cam as the main shaft is stopped, means for holding the presser-foot in raised position after the cam has moved out of engagement with said member, and means for moving said member 90 out of the path of the cam and for causing said holding means to release the presser-foot and allow it to descend on the work upon starting the machine.

FRED ASHWORTH.

Witnesses:

CHESTER E. ROGERS,
RUTH E. WARD.

It is hereby certified that in Letters Patent No. 1,233,539, granted July 17, 1917, upon the application of Fred Ashworth, of Beverly, Massachusetts, for an improvement in "Sewing-Machines," errors appear in the printed specification requiring correction as follows: Page 5, line 28, for the word "removed" read *is moved*; same page, line 116, for the words "of the head on" read *on the head of*; and that the said Letters Patent should be read with these corrections therein that the same may conform to the record of the case in the Patent Office.

Signed and sealed this 14th day of August, A. D., 1917.

[SEAL.]

R. F. WHITEHEAD,

Acting Commissioner of Patents.

Cl. 112—20.
